UNITED STATES PATENT OFFICE.

EZECHIEL WEINTRAUB, OF LYNN, MASSACHUSETTS, ASSIGNOR TO GENERAL ELECTRIC COMPANY, A CORPORATION OF NEW YORK.

VAPOR ELECTRIC DEVICE.

1,176,630.

Specification of Letters Patent. Patented Mar. 21, 1916.

Application filed March 27, 1914. Serial No. 827,621.

To all whom it may concern:

Be it known that I, EZECHIEL WEINTRAUB, a citizen of the United States, residing at Lynn, county of Essex, State of Massachusetts, have invented certain new and useful Improvements in Vapor Electric Devices, of which the following is a specification.

My present invention relates to vapor electric devices and particularly to vapor lamps which contain volatile halogen compounds.

In a copending application, Serial No. 827,579, filed concurrently herewith by Philip K. Devers, there is described and claimed a lamp of the so-called "high pressure quartz lamp" type supplied with conductive vapors of halogen compounds of metals, for example, the chlorides of tantalum or aluminum which add rays of desired color to the light. In this type of lamp great difficulty was caused by the interaction between the solid anode and the halid. Not only iron and nickel but even tungsten or tantalum, which are so valuable in the ordinary mercury quartz lamp, rapidly disintegrate in the arc containing vapors of halogen compounds and blacken the tube all over in a very short time. Carbon or graphite was found to disintegrate in the ordinary mercury quartz lamp and to even a larger degree in the lamp containing halids.

I have found that platinum and the metals of the platinum group, although they are capable of forming halogen compounds, are not affected by the halid vapors in the arc at the temperature at which the anode is running so that such an anode may be used in a high pressure lamp containing halid vapors without disintegrating and blackening the tube.

One form of vapor electric device equipped with an anode of platinum or a metal of the platinum group in accordance with my invention is shown in section in the accompanying drawing.

Ordinary platinum of commerce contains impurities, especially iron, which are attacked by the halids and cause slight blackening so that while commercial platinum can be used, it is much preferable to use chemically pure material.

In an ordinary quartz mercury arc lamp it is important to have the anode of a metal capable of withstanding a much higher temperature than the normal temperature at

tained when the lamp has reached its equilibrium; this because the initial starting current is much larger than the running current. This fact stands seriously in the way of using a platinum anode in the ordinary quartz mercury lamp. Fortunately in the arc containing halid vapors together with mercury vapor the conditions are such that there is a much smaller difference between the starting current and the running current so that the platinum anode can be kept at a good red heat during the operation of the lamp without fearing that it would reach too high a temperature beyond its melting point during the initial period before the equilibrium is reached.

In case of a large current lamp it may be necessary to raise the melting point of the anode metal and in all cases it may be desirable to reduce the amount of platinum used on account of the high price of metal. I find that the valuable property of high melting point possessed by tungsten and the chemical inertness toward halid vapors possessed by platinum can be combined by making the anode of a compound metal having a tungsten core and a platinum envelop. Other cores can be used if desired.

While my invention is not limited to any particular form of vapor electric device, the drawing shows for purpose of illustration a lamp of the high pressure mercury vapor type.

The envelop 1 shown in the drawing ordinarily consists of fused quartz as a material more refractory than glass is necessary because of the high temperature at which the device is operated. The lamp is provided at one end with the cathode chamber 2 filled with mercury, or an amalgam. The cathode chamber 2 is so proportioned that the coolest portion of the mercury pool is high enough to maintain the halid compounds vaporized. The anode 4 consists either entirely of platinum, or has a platinum surface. Leading-in wires 5 and 6 for the cathode and anode, respectively, are sealed into the envelop by the so-called graded seal being surrounded by a glass such as a sodium-magnesium boro-silicate, which in turn is joined to the quartz by a series of zones, each containing an increasing amount of quartz which passes from the seal to the quartz envelop. The leading-in wire is preferably tungsten and the platinum

anode is joined to the leading-in wire either by a fused joint or mechanically.

The lamp is provided with a halogen compound of a metal which at the temperature of the cathode is sufficiently volatile to insure the presence of vapor of the halogen compound in the arcing space during the operation of the device. As described in the above mentioned Devers application the halogen compounds of various metals such as tantalum, niobium, bismuth, antimony, arsenic and aluminum may be used.

The amount of halogen compounds will be varied in the nature of the device and the conditions of its operation but in most cases between about .007 and .1 gram will give a good result.

What I claim as new and desire to secure by Letters Patent of the United States,

29 is:—

1. A vapor electric device comprising an inclosing envelop, an easily vaporizable cathode, an anode at least the surface layer

of which consists of platinum, and a halogen compound in said envelop having a 25 boiling point approximating the operating temperature of the lamp.

2. A high pressure vapor electric device containing a halogen compound having a boiling point at least as high as the coolest 30 part of the cathode during the operation of the device and having coöperating electrodes, one of which consists of platinum.

3. A mercury vapor lamp comprising a silica envelop, a mercury cathode, a quantity of tantalum chlorid and an anode, at 35 least the surface layer of which consists of platinum.

In witness whereof, I hereunto set my hand this twenty fourth day of March, 40 1914.

EZECHIEL WEINTRAUB.
